UNITED STATES PATENT OFFICE.

CHARLES SCHMIDT, OF NEW YORK, N. Y., ASSIGNOR OF ONE-HALF TO
JOSEPH C. HOFFMANN, OF BROOKLYN, NEW YORK.

COMB.

No. 846,058.

Specification of Letters Patent.

Patented March 5, 1907.

Application filed July 21, 1906. Serial No. 327,209.

To all whom it may concern:

Be it known that I, CHARLES SCHMIDT, a citizen of the United States, residing at the city of New York, in the borough of Brooklyn and State of New York, have invented certain new and useful Improvements in Combs, of which the following is a full, clear, and exact description.

My invention relates to combs, particularly of that character worn by ladies for keeping the hair in place and for the purposes of ornament.

The principal object of my invention is to provide a comb of this character which may be securely fastened in its engagement with the hair, so as to avoid liability of loss by accident or theft.

A further object of the invention is to provide a two-part comb of which the component members are securely connected in use and which coöperate to lock the comb in place upon the hair and also to prevent the hair itself from becoming disarranged.

With these and other objects in view the invention consists in the features of construction and combinations of parts herein-after described and claimed.

In the drawings, Figure 1 is a view showing the comb applied. Fig. 2 is a view showing the comb separate from its locking-plate. Fig. 3 is a view showing the locking-plate. Fig. 4 is a view showing the locking-plate in position upon the comb. Fig. 5 is a detail view illustrating the manner in which the locking-plate is positioned upon the comb. Fig. 6 is a view similar to Fig. 5, showing the parts in a later stage of the engagement. Fig. 7 is a sectional view on the line VII VII of Fig. 4.

The ordinary construction of comb worn by ladies is very liable to become displaced in use, since the frictional engagement of the teeth thereof in the hair is the only means available for preventing such dislodgment.

As these combs are used for the purposes of ornament and are frequently more or less costly, it is very desirable to provide some means in addition to the mere frictional engagement of the teeth for precluding their accidental loss.

In carrying out my invention I make use of a locking-plate which has prongs specially constructed to engage the hair at points between the teeth of the comb. This lock-

ing-plate is designed to be engaged upon the comb by a simple and convenient manipulation and may, furthermore, be made so as to harmonize with the design of the comb and have an ornamental appearance.

Referring now to the drawings, in which like parts are designated by the same reference-sign, 1 indicates a comb having teeth 2 of the ordinary or any desired character. The usual form of comb is arcuate, so as to accord with the shape of the wearer's head. 3 indicates extensions upon each end of the comb 1, the lower edges of which are beveled, as shown at 4. The direction of these bevels is such as to impel the locking-plate onto the comb when these parts are properly engaged together.

A practical construction of locking-plate is particularly illustrated in Figs 3 and 7. This comprises a strip or plate 5 of sheet metal or other suitable material curved to correspond to the curvature of the comb 1 and bent backwardly at each end, so as to provide a pair of ears 6. These ears 6 engage the extensions 3, so as to guide the plate 5 upon the comb 1. The ears may therefore be said to constitute means for engaging the plate slidably upon the main portion of the comb 1 in the direction of the teeth thereof, since by reason of these ears the plate is guided to have such movement on the comb. Intermediate the ears 6 and along the lower edge of the locking-plate are a series of prongs 7, which are in the form of hooks bent around to project upwardly, as shown in Fig. 7.

The form and proportions of the locking-plate 5 is such as to slip over the comb 1, in which relation the ears 6 engage the bevel extensions 3 above described. The location of the prongs 7 is such as to fit between adjacent teeth 2 of the comb, said prongs projecting through the spaces between the teeth and upwardly on the reverse side of the comb. I provide means for fastening the locking-plate in proper relation upon the comb. A convenient construction is illustrated in Figs. 3 and 7, the same consisting of embossed protuberances 8 on the locking-plate, which spring into oppositely-located cavities 9 of the comb.

The use and operation of this invention will be clear from the preceding description. It is merely necessary to insert the comb 1 in

the hair and afterward manipulate the locking-plate 5 so that the ears 6 are engaged beneath the beveled edges 4 of the comb, in which relation the prongs 7 will enter slightly 5 among the folds of the hair. If the locking-plate is now pressed upward, the ears 6 are cammed inward by the bevels 4, as shown in Fig. 5, so that the locking-plate is closely applied to the comb, as shown in Fig. 6. At 10 the same time the prongs 7 enter the spaces between the teeth 2 and engage the folds or convolutions of the hair with sufficient firmness to prevent the withdrawal of the comb. The fastening means 8 serve to keep the locking-plate properly positioned upon the comb 15 as long as the device is in use. In order to remove the comb, the locking-plate is slipped downwardly by an operation which is in all respects the reverse of the procedure in applying the comb.

It is to be noted that the locking-plate 5 may be of any desired material or ornamental character and that this plate is the only part visible to any extent when the comb is 25 in use. Accordingly in practice I propose to have a number of plates of different styles, all of which are interchangeably applicable to a single comb, which may be of plain and inexpensive construction. In this way the 30 purchaser has all the advantages of a number of separate combs of different styles, and at the same time the comb proper is easily renewable in case it should be broken or otherwise damaged.

35 When my improved comb is applied as shown in Fig. 1, it is not only locked in place itself, but it also serves to hold the hair in place and prevent its disarrangement.

What I claim is—

40 1. A comb for ladies' hair, comprising a main portion having teeth and a locking-plate also having teeth curved or bent around so as to point reversely, means for engaging said plate slidably upon the main portion in 45 a direction longitudinal of the teeth thereof

so that the teeth of the plate pass upward between the teeth of the main portion to engage the hair of the wearer, and means for locking the plate in such relation after a predetermined amount of such upward slidable 50 movement.

2. A comb for ladies' hair, comprising a main portion having teeth and a back with lateral extensions, and locking-plate having teeth curved around so as to point reversely 55 and having ears which slide upwardly on said extensions, so that the teeth of the plate enter between the teeth of the main portion to engage the hair of the wearer.

3. A comb for ladies' hair, comprising a main portion having teeth and a locking-plate having teeth bent around to point reversely and adapted to pass between the teeth of the comb, said plate having ears bent 65 around to engage the main portion, and having means coöoperating with the main portion to hold the locking-plate in position.

4. In combination, a comb for ladies' hair, having a pair of extensions thereon, the lower edges of said extensions being beveled, 70 and a locking-plate having ears adapted to engage said beveled extensions and having prongs adapted to enter between the teeth of the comb.

5. In combination, a comb for ladies' hair, 75 having a pair of extensions thereon, the lower edges of said extensions being beveled, and a locking-plate having bent-over ears to engage said extensions and having prongs 80 to enter between the teeth of said comb, said locking-plate having protuberances thereon adapted to be received in corresponding recesses of the comb.

In witness whereof I subscribe my signature in the presence of two witnesses.

CHARLES SCHMIDT.
